UNITED STATES PATENT OFFICE.

JAMES HARNEY, OF BROOKLYN, NEW YORK.

DESIGN FOR VENTILATING-CAP.

Specification forming part of Design No. **7,635**, dated August 18, 1874; application filed July 3, 1874.
[Term of Patent 7 years.]

To all whom it may concern:

Be it known that I, JAMES HARNEY, of the city of Brooklyn, county of Kings and State of New York, have invented a Design for Ventilator or Ventilating-Caps, of which the following is a specification:

This invention does not relate to the construction of the ventilating-cap, as I have already claimed the devices of construction in an application therefor, and confined thereto, now pending in the United States Patent Office; but this invention herein described relates only to the design, as herein shown and described; and the nature of my design is fully represented in the drawings accompanying, to which reference is made, and in which—

Figure 1 is a perspective view of ventilator. Fig. 2 is an elevation of the same.

A represents the base of the structure. B represents a cap. C C are plates, standing

out from the base A, meeting at the top, forming an angle. D D are similar plates, the angle being reversed. A fancy open-work surrounds the base of cap, as shown.

The effect produced of light and shade, through the medium of the parts shown, as well as the general contour, is highly ornamental.

I do not claim, as in anywise a part of this application, the constructive parts of the ventilator; but

What I claim is—

The design for a ventilator-cap, consisting of the base A, pyramidal roof B, triangular plates C C and D D, substantially as shown and described.

JAMES HARNEY.

In presence of—

JOHN INGLIS, Jr.,
R. H. REILLE.
